UNITED STATES PATENT OFFICE.

JOHN H. NICOLSON, OF BIRMINGHAM, ALABAMA.

AUTOMATIC AIR-COUPING.

1,172,036.

Specification of Letters Patent. Patented Feb. 15, 1916.

Application filed November 12, 1914. Serial No. 871,751.

To all whom it may concern:

Be it known that I, JOHN H. NICOLSON, a citizen of the United States, residing at Birmingham, in the county of Jefferson and 5 State of Alabama, have invented certain new and useful Improvements in Automatic Air-Couplings; and I do hereby declare the following to be a full, clear, and exact description of the invention, such as will 10 enable others skilled in the art to which it appertains to make and use the same.

This invention relates to air line couplers used upon cars for the transportation of freight over railways and the primary object of the invention is the provision of an 15 automatic coupler whereby the air lines will be connected between a car and a train or between two cars upon the coupling of the cars in the ordinary manner and also to associate with the air coupling a valve construction and means for operating the same 20 whereby the valve will be opened for permitting the passage of air through the air line upon the coupling of cars.

Another object of the invention is the provision of springs of novel form for yieldably 25 mounting the air coupler to compensate for the backing or bumping action occasioned by the coupling of the cars.

Another object of the invention is the provision of means associated with and carried 30 by the receiving ends of the automatic coupler which will automatically position the inserting portion of the coupler in air 35 and fluid tight engagement with the receiver to prevent the leakage of air therethrough.

A still further object of the invention is the provision of means operable by the 40 means for drawing the draw pin or coupling-pin which will immediately cut out or close the valve which is interposed in the automatic air coupler as heretofore mentioned.

With the foregoing and other objects in 45 view this invention consists in such novel features of construction, combination and arrangement of parts as will be hereinafter more fully described, illustrated in the accompanying drawings and claimed.

In describing the invention in detail reference will be had to the accompanying 50 drawings wherein like characters designate like or corresponding parts throughout the several views, and in which:

Figure 1 is a top plan view of the im-

proved automatic air coupler. Fig. 2 is a side elevation of the improved air coupler showing the same attached to a freight car. Fig. 3 is an end view of the coupler showing the same attached to a freight car. Fig. 4 is 60 a cross sectional view on the line 4-4 of Fig. 1. Fig. 5 is a central sectional view through the improved automatic air coupler. Fig. 6 is a cross sectional view through the valve interposed within the 65 coupler. Fig. 7 is a detail view partly in elevation and partly in section of the manner of yieldably mounting the coupler. Fig. 8 is a cross sectional view on the line 70 8-8 of Fig. 2 and Fig. 9 is a cross sectional view on the line 9-9 of Fig. 3.

Referring more particularly to the drawings, 1 designates the receiving portion which has a substantially cubical or box like body portion 2. The body portion 2 of the receiving member 1 of the automatic air coupler has a flared mouth 3, which communicates with the interior of the box like body portion 2 and is provided for guiding the inserting member 4 which will be hereinafter more fully described. The body portion 2 of the receiving structure 1 has a boss 5 formed thereupon through which extends an opening 6. The inner end of the opening 6 has a gasket 7 mounted therein 80 and this opening has communication with a train pipe (not shown) of an ordinary air line brake system.

The inner side walls of the body 2 have slots 8 extending longitudinally therein, in which slots ride the pins 9. The pins 9 are formed at the junction between the arms 10 and 11 of the angled member 12. The under surface of the arm 11 rides upon a bushing 13 which is mounted about the surface of a bolt 14. The bolt 14 extends laterally across the body 2 and the bottom of the body 2 is cut away as is shown at 15 to accommodate the bolt 14 and sleeve 13. The receiving member 1 has a supporting bracket arm 16 secured thereto, which extends upwardly from the receiving structure 1 and has its upper terminal end bent angularly to the body portion thereof for resting upon the upper surface of an ordinary 100 coupler illustrated at 17, such as are used on freight cars of ordinary construction. The supporting bracket 16 is held against pivotal or longitudinal movement independent of the coupler 17 by set screws 18 105 110

which are inserted through the bracket 16 and extend into the coupler.

The receiving structure 1 has an arm 20 formed integrally therewith and projecting transversely therefrom, to which arm is connected a casing 21. The casing 21 has a pipe 22 inserted thereinto, from the rear end of the same, which pipe has its forward end screw threadably connected to a sleeve 23. The sleeve 23 has an annular flange 24 formed upon its rear end, which rides in the bore of the casing 21. The inner end of the sleeve 23 has an annular groove 25 formed therein which receives one end of an expanding spiral spring 26. The spiral spring 26 is coiled about the pipe 22 and has its end which is free from engagement with the annular recess 25 in engagement with the inner surface of the end wall 27 of the casing 21, for yieldably holding the sleeve 23 within the casing 21. The casing 21 has its forward end open and the sleeve 23 which tapers as it extends outwardly from the casing projects therefrom. The sleeve 23 is provided with a longitudinally extending bore 28 which communicates with the interior of the pipe 22 and with the angled bore 29 which is formed in the head 30 of the inserting coupling members 4, of which the sleeve 23 and casing 21 and pipe 22 are a part. The head 30 of the inserting structure 4 is substantially spherical and it has a lug 31 formed thereupon which lug is provided with an internally screw threaded opening 32 formed communicant with the bore 29 for receiving the reduced end of the sleeve 23 for attaching the head 30 to the sleeve 23 in substantially fluid tight engagement. The angled bore 29 of the head 30 is adapted for alignment with the bore 6 which is formed in the boss 5 for completing a continuous passage between two meeting cars of a train upon the couplings of the same. The body 2 has a depending lug 33 formed therein which has its under surface arcuate for conforming to the surface of the ball and for forming an abutment against which the ball strikes for limiting the inward movement of the same. The arm 20 has guideways 35 formed upon its under surface to which is secured one end of a flat spring 36. The flat spring 36 is coiled, intermediate of its end to form a resilient convolution as indicated at 37, and it extends upwardly from the convolution having its terminal end bent angularly and slidably seated in guideways 38 which are carried by the draw bar of an ordinary freight car 41. By slidably supporting the angled terminals of the flat spring 36, and also by the resilient convolution which is formed within the springs, the automatic air coupler will be yieldably mounted upon a car for yieldable movement upon the coupling or un-

coupling of the cars. The casing 21 of the inserting structure 4 has lugs 45 formed integrally with one side thereof, to which lugs are secured in any suitable manner the lower end of a pendant bracket 46 which has its upper end angled for resting upon the upper surface of an ordinary car coupler 17. The pipe 22 is connected to a pipe joint 50 which pipe joint forms a valve seat having a valve 51 seated therein. The pipe joint 50 has a pipe 52 communicant therewith directly opposite to the communicating end of the pipe 22 and the valve 51 is provided with an opening 53 extending transversely therethrough and communicating with the bores of the pipe 22 and 52. A pipe 54 extends from the joint 50 at substantially right angles to the pipes 22 and 52 and it is connected to the boss 5 and the opening 6 formed in the receiving head so as to provide a communication between the receiving head and the air line 55 of a train. The air line 55 has communication with a T-joint 56 with the pipe 52 and an ordinary type of air coupler 57 is attached or connected to the T-joint 56 so that in cases where it is desired to couple a car with the automatic coupler to one who is not provided with the same, the ordinary type of air line connection may be employed. The valve 51 has an opening 58 formed therein extending transversely to the opening or bore 53 communicant therewith and provided for communication with the bore of the pipe 54.

The stem 59 of the valve 51 projects from the joint 50 parallel with the pipe connection 54 and has an angle lever 60 rigidly secured to its outer end. The angle lever 60 has a flexible member 61 connected to its arm 62 thereof, which arm normally rests in a horizontal plane. The flexible member 61 is connected to the portion 63 of the rod 64. The rod 64 is of the ordinary type of draw pin operating rods such as are carried by the ends of freight cars and has a handle 65 formed thereupon for rocking the rod for pulling the draw or coupling pin 66 to permit of the uncoupling of the car. Upon the rocking of the rod or shaft 64 to draw the pin 66, the arm 62 will be drawn into a horizontal plane, which will position the arm 67 of the angle lever 60 in a vertical position as indicated in dotted lines in Fig. 2 of the drawings. A sill 68 of a freight car has a bracket 69 secured thereto. The bracket 69 has a plate 70 hingedly connected substantially U-shaped frame 71, which is slidably carried by transversely extending guideways 72 which are formed upon opposite sides of the bracket 69. The plate 70 is hingedly connected as is shown at 73 to the vertex of the U-shaped frame 71 and it is permitted of forward swinging movement but prevented of rearward swinging movement.

by the back of the bracket 69 as is clearly shown in Fig. 9 of the drawings. The plate 70 depends from the bracket and is positioned so that its lower end will strike the upper end of the arm 67 of the angled lever 60 for moving said arm forwardly and positioning the arm 62, for opening the valve 51 for establishing communication with the various pipes associated therewith. The plate 70 has an eye bolt 74 secured thereto to which eye bolt is connected a flexible member 75. The flexible member 75 extends upwardly and is connected to the U-shaped portion 63 of the rod 64 so that upon the rocking of the rod 64 the frame 71 and the plate 70 will be moved upwardly in the guideways 72 to permit of the arm 67 assuming a vertical position.

In the operation of the automatic air coupler heretofore described; when two cars equipped with the improved air coupler are coupled together by means of the ordinary coupler, the sleeve 23 and the ball or head 30 mounted thereupon will enter the flared mouth 3 of the receiving structure 1 and the ball will ride upon the upper surface of the arm 11 and the angled member 12, which arm is positioned at an incline, having inclined under surface resting upon the upper surface of the base of the box or casing 2, and inward forcing movement of the head 30 will move the arm 11 to substantially a horizontally position and after the ball has become seated in the arcuate recess 61^a formed in the upper surface of the arm 11, the member 12 will ride rearwardly within the casing upon the sleeve which is mounted about the bolt 14, and force the ball upwardly into firm binding engagement with the inner surface of the depending lug 33 and into firm binding engagement with the gasket 7 for forming substantially a fluid tight connection between the ball or head 30 and the opening 6 and consequently the air pipe of the car to which the receiving structure 1 is attached.

The rearward movement occasioned by the coupling or bumping of the two cars together will cause the entire arrangement to move rearwardly a short distance and open the valve 51 so that communication may be established between the air pipe of the two cars.

The uncoupling of the cars in the ordinary manner, will when one car is drawn from the other, draw the ball or head 30 out of the receiving structure 1, moving the lever so that the arm 11 will rest against the base of the box or housing 2. The uncoupling of the cars, by the operation of the rod which draws the coupling pin will operate the plate 70 as heretofore described, closing the valve 51.

From the foregoing description taken in connection with the accompanying drawings

the advantages of the construction and of the method of operation of the improved automatic air coupler will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

What is claimed is:

1. In an automatic air coupler, a yieldably supported spherical head having communication with a train line, a receiving casing having an outlet, a gasket surrounding said outlet, and a substantially L-shaped member 85 slidably seated in said receiving casing for receiving said head upon insertion into the casing.

2. In an automatic air coupler, a yieldably supported spherical head having communication with a train line, a receiving casing having an outlet, a gasket surrounding said outlet, a substantially L-shaped member slidably seated in said receiving casing for receiving said head upon insertion into the 95 casing, a bushing rotatably mounted within said casing for engaging said substantially L-shaped member and forcing said spherical head into fluid-tight engagement with said gasket upon the insertion of the head into 100 said casing and rearward movement of said L-shaped member.

3. In an automatic air coupler, a yieldably supported spherical head having communication with a train line, a receiving casing having an outlet, a gasket surrounding said outlet, a substantially L-shaped member slidably seated in said receiving casing, said L-shaped member having the upper surface of its base recessed for receiving a portion 105 of said spherical head for limiting the inward movement of the head independent of movement of said L-shaped member, a bushing rotatably mounted within said casing for engaging said L-shaped member upon rearward movement of the same within said casing for forcing said spherical head into fluid-tight engagement with said gasket.

4. An automatic air coupler comprising the combination with an inserting member comprising a casing, a stem having one end slidably mounted within said casing, said stem having communication with an air line pipe, a ball head formed upon the other end of said stem, of a receiving member comprising a casing, a gasket formed within said casing and having communication with the air line of a car, a bolt extending transversely through said casing, an angle member 125 slidably carried by said casing and seat-

ed upon said bolt for engagement with said ball head for forcing the same into fluid-tight engagement with said gasket.

5. In an automatic air coupler the combination of an inserting member comprising a casing, a stem having one end slidably mounted within said casing, said stem having communication with an air line pipe, a ball head formed upon the other end of said 10 stem, a receiving member comprising a casing, a gasket formed within said casing and having communication with the air line of a car, a bolt extending transversely through said casing, an angle member slidably carried by said casing and seated upon said bolt for engagement with said ball head for forcing the same into fluid-tight engagement with said gasket, and means for yieldably connecting said receiving member and said 15 20 inserting member to a car for permitting of yieldable movement compensating the bumping of the car.

6. In an automatic air coupler, an inserting structure comprising a casing, a pipe extending into said casing and having communication with a car air pipe, a stem having an annular flange formed upon one end,

said flange seated in said casing, a spiral spring seated in said casing and engaging said flange for yieldingly connecting said stem and said casing, said stem being provided with a bore communicating with said pipe, a substantially spherical head detachably mounted upon the outer end of said stem and having an angled bore extending therethrough, a receiving structure including a casing, a gasket carried by one side of said casing and having an opening extending therethrough which communicates with a car air pipe, an angled member carried by said casing for engagement with said head upon insertion into said casing, and a rotatable bushing carried by said casing and engaging said angled member for forcing said head into firm fluid-tight connection with said gasket upon insertion of said head into said receiving casing.

In testimony whereof I affix my signature in presence of two witnesses.

JOHN H. NICOLSON.
